ELECTRIC SWITCH

Original Filed Jan. 24, 1923

UNITED STATES PATENT OFFICE.

JOHN E. SPRINGER AND ROBERT A. HARRY, OF BALTIMORE, MARYLAND.

ELECTRIC SWITCH.

Application filed January 24, 1923, Serial No. 614,642. Renewed December 2, 1925.

Our invention relates to improvements in switches and an object of the invention is to provide an improved switch especially for the parking light of an automobile adapted 5 to automatically close the electric circuit of the parking light at any set predetermined time.

Another object of the invention is to provide a combined clock and switch, the latter being so embodied in the clock that when the proper set time arrives, the electric circuit of the parking light or the like will be closed.

Other objects and advantages will appear 15 in the following specification, reference being had to the accompanying drawings, in which:

Fig. 1 is a rear elevation of a part of the instrument board showing the control in place,

Fig. 2 is a detail perspective view of a part of the control,

Fig. 3 is a similar view showing the associated parts of the setting lever disassembled, and

Fig. 4 is a detail perspective view of part of the clock mechanism and showing the circuit closing devices.

It is not an uncommon experience for the 30 driver of an automobile to leave the automobile parked at the curb at a time when lighting the parking light is not yet necessary, and then forget to come out and turn the light on. Failure to show a parking light after a certain time in the evening is 35 subject to a penalty in many communities. The express purpose of the invention described below is to make provision for automatically turning the electric current of the parking light on at any predetermined time.

This provision consists of a clock 1 which is mounted behind the instrument board of the automobile. In Fig. 1 the instrument board is indicated at 2. The case of the clock has a plurality of ears 3 through which screws 4 pass in order to support the clock as stated.

The instrument board is provided with a 50 slot 5 immediately above the clock. A setting lever 6 projects through this slot and has the end 7 turned up so as to make it more convenient to operate the lever and at the same time prevent the lever from 55 extending out so far as to possibly catch

the clothing of the operator in getting in and out.

Although the face of the clock does not show in the drawings, the reader will understand that it consists of the ordinary well-known time piece. Only so much of the mechanism of the clock is shown as relates directly to the invention. In Fig. 4, the star wheel 8 comprises that portion of the alarm mechanism of the clock that operates 60 the double pawl 9.

This star or ratchet wheel 8 controls the vibration of a contactor 10 which is carried by the shaft 11 upon which the double pawl 9 is mounted. This contactor may either be 65 used in substitution of the usual alarm striker 12 or may accompany the latter as may be desired. In Fig. 4, both are shown in place on the shaft 11.

The end of the contactor 10 is bent over 70 at right angles and terminates in a pair of spring fingers 13. These are adapted to engage and grip a contact 14 which depends from the manually operable setting lever 6. This lever is pivotally mounted at 15 on the 75 case of the clock. The screw which constitutes the pivotal mounting, also serves as the ground connection of a wire 16 (Fig. 2) which in practice runs to one terminal of a 80 battery.

Another wire 18 (Fig. 2) has electrical connection with the contact 14. This pin passes through a hole 19 in the setting lever 6 which, like the slot 20 in the clock case is sufficiently large to let the contact pass 85 through without touching. A pair of non-conducting washers 21 insulate the contact from the setting lever. A nut 22 is screwed on the threaded part of the contact to hold it in place when in proper position.

The wire 18 in practice also has connection with one side of a parking light (not shown), the other side of the parking light having connection with the aforesaid battery through a suitable wire. This completes the electrical circuit. The clock 1, like all clocks of this character, includes a key 25 by which the alarm spring 26 is wound. The face of the clock is adapted to show through a suitable opening in the instrument board 2, and in order to wind the clock, the operator must reach up under the instrument board so as to reach the key 25.

The operation is as follows: Assume the 110

alarm mechanism of the clock 1 to have been set to go off at a predetermined hour of the evening. The operator of the automobile is assumed to have done this before leaving the automobile. At the time set, the alarm mechanism will start to operate and tend to vibrate the contactor 10 in the manner that the ordinary striker is customarily vibrated.

However, the spring fingers 13, in moving over toward the right, in Fig. 4, will catch and grip the contact 14 so that an electrical circuit is completed from the battery and the parking light, said circuit also including the contactor 10 and metal of the clock mechanism to the wire 16 and back to the battery.

The parking light is now supposed to be lighted and remains so until the operator returns to the automobile. He then moves the handle 7 in the direction indicated in Fig. 2, thereby releasing the contact 14 from the engagement of the spring fingers 13 and opening the electric circuit for the extinction of the parking light. It is thus seen that the control or switch first functions by mechanically moving a contactor into engagement with a contact for the completion of a circuit, and next manually moving

the contact from said contactor to break the circuit.

In conclusion, it is desired to say that the improved switch may be made to govern more than one parking light. It is anticipated that same communities require both a front and rear parking light. It is quite obvious that the electrical circuit described may embrace both the front and rear parking light so that both will be illuminated at the set time.

We claim:—

A device of the character described comprising a clock mechanism at which one end of an electric circuit is grounded, a setting lever, means by which said lever is pivoted on the clock case and by which said ground is established, a contactor embodied in the clock mechanism and adapted to be vibrated thereby at a set time, a contact pin to which the other end of the circuit is connected, and means by which said pin is insulatively mounted on the lever, said lever being adapted to either sustain the pin in an engageable or non-engageable position in respect to the contactor.

JOHN E. SPRINGER.
